EDWARD C. BELL AND RAYMOND S. CASE, OF UNIONVILLE, CONNECTICUT.

STRIP OF MATERIAL FOR FORMING CARTRIDGE-SHELLS.

1,206,501.

Specification of Letters Patent. Patented Nov. 28, 1916.

Application filed August 15, 1914. Serial No. 856,977.

To all whom it may concern:

Be it known that we, EDWARD C. BELL and RAYMOND S. CASE, each a citizen of the United States, residing at Unionville, in the 5 county of Hartford and State of Connecticut, have invented a new and Improved Strip of Material for Forming Cartridge-Shells, of which the following is a specification.

10 Our invention relates to the formation of tubes from which cartridge shells are made, and an object of our invention, among others, is to provide a strip of material having such characteristics as to enable a shell 15 of superior quality to be produced in a particularly efficient manner.

One form of strip embodying our invention and in the construction and use of which the objects herein set out, as well as others, may be attained, is illustrated in the accompanying drawings, in which—

Figure 1 is a face view of a strip of material embodying our invention. Fig. 2 is a view in section through the same, the thickness being exaggerated to illustrate the invention and the water-proof coating being indicated by a thick black line.

In the making of paper shells employed to hold a charge of powder, a tube is generally formed and is then cut up into pieces of the proper length to form the shells which are supplied with caps and other devices to complete the shell.

It is desirable that the inner surface of the completed shells shall be coated with a material, as paraffin, which while objectionable to a certain degree is of particular and the greater advantage in that it prevents the inner surface of the shell from being scorched or burned when the powder is ignited. This paraffin may be applied in the simplest and most efficient manner, by dipping the shells in baths of melted paraffin. It is observed that this dipping process will treat the outside as well as the inside of the shell, and while it is essential that the outside of the shell shall be water-proof to prevent it from being detrimentally affected by changes in atmospheric conditions, it is inadvisable to use paraffin for this purpose, for the reason that it injures the fibers of the paper to a certain degree. The advantages of the paraffin are such as to require its use on the inner surface of the shell and it therefore becomes imperative

that some means shall be provided for preventing its contact with the outer surface of the shell. Our invention accomplishes this end and provides a paper strip that may be formed into a tube for the production of 60 shells, which tube or shells may be dipped in melted paraffin and the latter will come in contact with the paper only on the inner surface where its presence is practically required. 65

In the accompanying drawings the numeral 5 denotes a strip of paper or similar material that is of a width equal to the length of the tube to be produced therefrom. The edge 6 of this paper is treated with a 70 water-proofing material, to an extent equal to or slightly greater than the circumference of the tube to be finally produced from the strip, so that the entire outer surface of the tube will consist of this water-proofed material. In many instances it is desirable to have the shells colored and in such cases coloring material may be mixed with the water-proofing material or separately applied to the paper, the colored portion being 75 coextensive with the water-proofed portion. This strip now possesses such qualities that when a tube is produced therefrom the entire outer surface will be a water-proof one, and after this formed tube is dried it may 80 be treated in a bath of melted paraffin. It will be seen that the characteristics of the tube are such that the paraffin will not penetrate the outer surface to any extent but will be located only on the inner surface of 85 the tube where it is required to produce beneficial results in preventing the shells from being scorched or burned in the discharge of the explosives therein. The water-proofing material thus protects the outer surface of the shell from any injurious effects of the paraffin and when the coloring material is applied in the water-proofing, this material also prevents the color from running under the influence of 90 the hot, moist paraffin. 95

We claim—

1. A strip of material for the production of tubes to be formed into cartridge shells, said strip having its edge treated with a protective coating to prevent contact of paraffin therewith, said coating extending a distance equal to the circumference of a tube to be formed from said strip. 105

2. A strip of material for the production 110

of tubes to be formed into cartridge shells, said strip being of a width to produce a shell of several plies, said strip being in its natural state from one edge to such distance from the opposite edge as will comprise a margin equal to the circumference of the shell, such margin being treated with col-

ored protective coating to prevent contact of paraffin therewith.
